UNITED STATES PATENT OFFICE.

JAMES BROWN, OF SAN FRANCISCO, CALIFORNIA.

FOOT-CORRECTOR.

1,191,122.

Specification of Letters Patent. Patented July 11, 1916.

Application filed October 5, 1915. Serial No. 54,152.

To all whom it may concern.

Be it known that I, JAMES BROWN, a citizen of the United States, residing in the city and county of San Francisco and State 5 of California, have invented new and useful Improvements in Foot-Correctors, of which the following is a specification.

This invention relates to a foot corrector.

The object of the present invention is to 10 provide an insert for shoes by which the longitudinal and transverse arches of the foot may be supported and the metatarsal phalangeal articulative points balanced, in this manner making it possible to correct 15 various ailments of the feet, such as bunions, callouses, corns of various kinds, hammer toes, cramps of the muscles, etc.

The invention consists of the parts and the construction and combination of parts, 20 as hereinafter more fully described and claimed, having reference to the accompanying drawings, in which—

Figure 1 is a perspective view of the insert. Fig. 2 is a bottom view of same. Fig. 25 3 is a cross section on line 3—3, Fig. 2, Fig. 4 is a perspective view of one form of insert used to support the longitudinal arch of the foot.

Referring to the drawings in detail, A 30 indicates in general, an inner sole or what is commonly known as an insert, which is adapted to be placed in a shoe. The insert is in this instance, cut or shaped approximately as shown and constructed of leather 35 which is placed between dies and pressed therein, to form a recess or depression 2, for the heel and a raised portion 3, to support the longitudinal arch or instep of the foot and raised, as at 4 to support the trans- 40 verse arch of the foot. The bottom side of the insert A is lined with a thin section of leather 5, which is secured to the insert by being stitched thereto, as indicated at 6. The stitching 6 runs all around the edge of 45 the insert except at the points, indicated at 7 and 8, where a curve 9 is made which conforms with the raised portion 3 that supports the longitudinal arch of the foot. The stitching is also carried across the front 50 portion of the insert, as at 10, at a point rearwardly of the raised portion 4; two pockets 11 and 12 are in this manner formed between the insert proper and the lining 5; the pocket 12 being provided for the pur- 55 pose of receiving one or more pads or inserts 13, while the pocket 11 is provided for

the purpose of receiving a pad, such as indicated at 14, see Figs. 2 and 3. Inserted between the lining 5 and the insert proper, is a strip 15, which extends across the mouth 60 of the pocket 12, this strip is provided to prevent the raised portion 3 from flattening out or losing its shape and it also serves as a means for retaining inserts, such as indicated at 13, when these are placed 65 in the pocket. The pocket, indicated at 11 is entirely inclosed by the stitching, indicated at 6 and 10. It is, therefore, necessary to slit the lining at a plurality of points, such as indicated at 16; the slitting 70 of the lining at the several points permits the pad 14 to be inserted at any point within the pocket, and it may be further secured at the point inserted by applying an adhesive or other means. The shape and thick- 75 ness of the pads, indicated at 13 and 14, together with the material and finish of same permits their construction to be varied to suit conditions.

The device as a whole, is provided for 80 the purpose of alleviating or curing different ailments of the feet. As an illustration, the following examples are given: If it is desired to cure a bunion on the large toe, the cushion or pad 14 is moved under 85 and behind the head of the connected metatarsal articulative point, where it will engage the ligament that controls the large toe; the pressure thus applied, holds the ligament taut and brings the toe back to position, thus curing the bunion and eliminating operation. Again, if it is desired to cure a case of callous under the main supporting points on the front portion of 90 the foot, a comparatively large cushion or pad 14 is inserted between the inner sole and the lining 5, to assume the position shown at 17, see Fig. 2. The main weight of the foot is thus supported on the center of the transverse arch, thus relieving the 100 callouses of the main weight and consequently curing the same. It will be seen that where crooked toes or what is known as hammer toes are to be cured, it is only necessary to adjust the position of the pad 105 to a point behind the head of the metatarsal articulative points of the toe to be treated, where it will engage the connected ligament and apply sufficient pressure to pull the ligament taut and bring the toe back to nor- 110 mal position.

Corns of various kinds are also cured by

the application of this device, as the toes may either be spread apart, where soft corns between the toes are to be cured, or lifted into position by securing the pad in a position 5 where it will apply sufficient pressure to tighten the connected ligaments and cause these either to spread or lift the toes into the desired position. Running over of the feet on one side or another is similarly corrected, as it is only necessary to move the pad from one side of the foot to the other, as the case may be. One of the cushions is extra large and so shaped, as to segregate the ankylosed articulative points, and being 10 movable at the patient's will, can easily overcome cramp or nerve pinch. The instep or longitudinal arch of the foot is similarly supported by inserting one or more pads, such as indicated at 13; the height to which 15 it is desired to raise the instep is determined by the number of pads inserted or by the thickness of same.

The device as a whole, is simple, compact in construction, cheap to manufacture, being 20 provided with pockets it is possible to insert pads of different sizes and thicknesses. It is easy to adjust the device to relieve pressure on the foot at any point or accomplish any result desired; in this manner, not only alleviating pain, but also curing ailments of 25 various kinds.

The provision of the several slits 16, permits the pad 14 to be inserted at any point; this is important, as the pad must necessarily 30 be moved to assume different positions, when treating different cases. This slitted or strap-like structure is also important, as it permits the insertion of pads of varying thickness.

40 The materials and finish of the several parts of the device may be such as the judgment and experience of the manufacturer may dictate.

I wish it understood that various changes 45 in form, proportions and minor details of construction may be resorted to within the scope of the appended claims, and that I do not wish to limit myself to the specific design and construction here shown.

Having thus described my invention, what 50 I claim and desire to secure by Letters Patent is—

1. A foot corrector comprising an inner sole, a lining piece stitched to the bottom side of the sole, said lining member being 55 slitted at a plurality of points near the front end, and a pad member insertible between the sole and the slitted lining to thicken the sole at a point registering with the transverse arch of the foot.

2. A foot corrector comprising an inner sole and a transverse strip stitched to the bottom of the sole forming an inclosed pocket near the toe portion, said strip being slitted in several places to allow an insert at different 60 points transversely of the sole.

3. In a foot corrector, a member having a raised part forming a pocket thereunder, and a tensioning element secured to said member and disposed beneath the raised part and being spaced from the inner longitudinal side of the pocket to admit inserts in said space between the element and the pocket inner side and to hold the insert in the pocket.

4. A foot corrector composed of a member 75 having a pocket the bottom of which is formed with a series of spaced slits providing straps connected at each end to the bottom and having each of their sides free, whereby to engage an insert by extending 80 thereacross and intermediate opposite sides or ends of the insert.

5. In a foot corrector, a member having a raised part forming a pocket thereunder, and means secured to said member and disposed beneath the raised part and being spaced from the inner longitudinal side of the pocket to admit inserts in said space between the means and the pocket inner side and to hold the insert in the pocket.

In testimony whereof I have hereunto set my hand in the presence of two subscribing witnesses.

JAMES BROWN.
